UNITED STATES PATENT OFFICE.

ALFRED O. ANDERSON, OF LEVIS, CANADA.

SAFETY-ENVELOP.

SPECIFICATION forming part of Letters Patent No. 710,731, dated October 7, 1902.

Application filed March 10, 1902. Serial No. 97,403. (No model.)

To all whom it may concern:

Be it known that I, ALFRED OLAUS ANDERSON, a subject of His Majesty the King of Great Britain, residing at Levis, county of 5 Levis, Province of Quebec, Canada, have invented certain new and useful Improvements in Safety-Envelops; and I do hereby declare that the following is a full, clear, and exact description of the invention, such as will enable others skilled in the art to which it appertains to make and use the same.

This invention relates to improvements in safety-envelops of that class in which is employed a sealing-strip or the like; and it has 15 for its objects, among others, to provide a simple and cheap, yet most durable and efficient, device for holding money or other valuables in envelops in such a manner that when the envelop is sealed it will be impossible to remove the valuables without destroying the seal or the envelop. It is designed to obviate the necessity of stitching the money and envelop, as heretofore, which stitching, though safe, destroys the bills, and, further, consumes 25 too much time.

The device is of such a nature that it can be applied readily to any envelop and any one can apply it.

Other objects and advantages of the invention will hereinafter appear, and the novel features thereof will be specifically defined by the appended claims.

The invention is capable of embodiment in a variety of forms, the preferable one being 35 herein illustrated.

In the annexed drawings, forming a part of this specification, Figure 1 is a perspective view of my improved safety device. Fig. 2 is a view showing it in the position it assumes 40 when first applying it to a package of banknotes. Fig. 3 is a view of the opposite side of the package, showing the parts in their position after the ends of the arms have been folded under the guards or flanges. Fig. 4 is a view of the same side of the package just 45 before the said arms are placed under the flanges. Fig. 5 is a cross-section on the line 5 5 of Fig. 6. Fig. 6 shows the envelop enclosing the package ready to receive the seal. Fig. 7 is a view of the cap employed.

Like characters of reference indicate like parts in the different views.

Referring to the drawings, 1 designates the sealing-strip, which, as seen in Fig. 1, comprises the body portion 2, the arms 3, and the 55 prongs 4. The arms 3 are of less width than the body portion, being each practically one-half the width of the said body portion, and they extend from diagonally opposite corners of the said body portion, as seen in Fig. 1. 60 The strip may be made of any suitable bendable material having the required strength to enable it to withstand the wear to which it is subjected, and the arms may be of any required length. It may be found advisable to 65 construct them of different lengths, so that a strip may be selected suited to the size of the package.

The prongs 4 are stamped out from the strip at the junction of one of the arms with 70 the body portion, as seen clearly in Fig. 1, and extend in opposite directions from a median line through their bases or points of junction with the material from which they are struck.

There is a flange 5 at the inner end of the arm adjacent these flanges or prongs 4, the portion of the body extended beyond the other arm forming another flange 6, beneath which flanges the free ends of the arms are designed 80 to be disposed when the package is ready to be inclosed within the envelop.

The strip is provided with a series of indentations 7, as seen, and which are designed to be embedded in the bank-notes or other 85 valuables to hold the strip against shifting its position when once in place thereon.

8 is a cap of any suitable material. It is provided with a slot 9, disposed substantially diametrically of the cap for the passage of 90 the prongs 4 of the strip, and this cap is provided upon one face with adhesive material, as seen at 10.

In practice the bank-notes or other papers 11 are placed in position on the body portion, 95 the arms being disposed at right angles to the said body portion, and after the papers are placed in position then, pressing down on the edges of the papers with the fingers, the arms 3 are folded over alternately, as 100

seen in Fig. 2. The package is then turned with the other side up and the cap 8, which had been previously held in position by the prongs 4 passing through the slot 9, is removed 5 by first lifting the two prongs so they shall extend at right angles to the body portion and then removing the cap. The arms 3 3 are then folded around the package into the position in which they are seen in Fig. 4 and 10 then slipped under the flanges or flaps 5 and 6, as seen in Fig. 3. Then the strip is struck a light blow with a hammer, paper-weight, or any other convenient article, so that the indentations or points 7 are forced into the 15 bills, which will prevent displacement of the strip on the papers. The package is then placed within the envelop 12, the prongs forced through the same, the cap moistened upon its gummed side and replaced, as seen 20 in Fig. 6, and then a cord or string or tape 13 is passed under one of the prongs 4 and the latter bent down upon the cap, and after passing the cord or string around the envelop, as seen in Figs. 5 and 6, its other end is en- 25 gaged with the other prong 4, which is likewise bent down upon the cap, and then the envelop is sealed with just sufficient wax to make a clear impression. The heat from the wax will make the cap adhere. 30 To open, cut the string and open the side of the envelop, then remove the contents, tearing away that part of the envelop between the seal and the edge, thus preserving the seal, and count the money before removing the 35 sealing or fastening strip.

The strip may be used over and over again. The flanges 5 and 6 protect the free ends of the arms and serve to hold them against accidental displacement, and then they are pre- 40 vented from projecting through the envelop.

The slight indentures made in the bills by the projections 7 are not sufficient to injure the bills.

Modifications in detail may be resorted to without departing from the spirit of the invention or sacrificing any of its advantages. 45

Having thus described my invention, what I claim as new is—

1. A device of the character described, consisting of a strip with arms at its opposite ends a body portion of greater width than the arms and forming flanges beneath which said arms are designed to be disposed, and prongs extending from the body portion at the junction therewith of one of said arms. 50

2. The combination with a strip having arms and prongs and flanges beneath which the free ends of said arms are designed to engage, of a cap having a slot for the passage of said prongs. 60

3. The combination with a bendable strip having arms, prongs and flanges beneath which the free ends of said arms are designed to engage, of a cap having a slot for the passage of said prongs, and provided upon one 65 side with adhesive material.

4. The fastening and sealing strip herein described, formed of a single piece of bendable material and comprising a body portion, arms extending from opposite ends and from diagonally opposite corners of said strip, and prongs struck up from the strip at the junction of one of said arms with the body portion and in opposite directions. 70

In witness whereof I have hereunto set my 75 hand in the presence of two witnesses.

ALFRED O. ANDERSON.
